UNITED STATES PATENT OFFICE.

HERMAN E. HEINE, OF MILWAUKEE, WISCONSIN, ASSIGNOR TO BRADLEY WASH-
FOUNTAIN CO., OF MILWAUKEE, WISCONSIN, A CORPORATION OF WISCONSIN.

LIQUID-SOAP DISPENSER.

Application filed July 14, 1923. Serial No. 651,532.

The main objects of the invention are to supply small predetermined quantities of liquid soap particularly to users of lavatories; to avoid waste of soap and unsanitary conditions; and generally to simplify and improve the construction and operation of devices of this class.

It consists in the construction, arrangement and combination of parts as herein-
10 after particularly described and pointed out in the claims.

In the accompanying drawing like characters designate the same parts in both figures.

15 Figure 1 is a medial vertical section on the line 1—1, Fig. 2, of a device embodying the invention as connected with a liquid soap receptacle; and Fig. 2 is a horizontal cross section on the line 2—2, Fig. 1.

20 The device, which is designed to be attached to a liquid soap receptacle for use in connection with lavatories, particularly such lavatories as are used in public places and are intended for the simultaneous ac-
25 commodation of a number of persons, com-
prises a main body or case 1, which with slight modification may be installed either in a vertical or a horizontal position, is formed with a receiving chamber 2 and an
30 inlet passage 3. As shown, the case or body 1 is designed to be connected in a vertical position with a liquid soap receptacle 5, to which a number of like dispensing devices 35 may be attached for use by a number of persons at the same time.

The case or body is formed at its lower end with a laterally projecting branch 6, in which the inlet passage 3 is formed, and which has an enlarged internally threaded 40 socket at its outer end for screwing it up-
on the outwardly projecting threaded end of an elbow-shaped nipple 7, which is connected at its inner upper end with the bottom of the soap receptacle 5.

45 The inlet passage 3 is enlarged at its inner end, which communicates with the lower end of the chamber 2 and forms a valve chamber 9 of smaller diameter than said chamber 2. An inwardly opening ball 50 check valve 10 is loosely confined in the chamber 9 by a perforated cover plate 11, and is provided in the lower part of said chamber with a conical seat 12 against which it closes, to prevent backward flow of soap 55 from the chamber 2 through the passage 3.

A shouldered cap 14, removably threaded in the upper end of the case 1, is formed with a discharge chamber 15, coaxial with and of smaller diameter than the receiving chamber 2, into the upper end of which 60 it opens. Around the opening at the lower end of the chamber 15, the cap is formed with an annular valve seat 16, and above said chamber it is provided with a laterally projecting delivery spout 20, which com- 65 municates at its inner end with the upper end of the chamber 15.

A plunger 22, freely fitting in the chamber 2, is recessed on its upper side and provided with a valve disk 23, of suitable elastic, pliant or soft material such as leather or vulcanized fiber, adapted to form a tight joint with the seat 16, against which it closes. The plunger is provided with an operating stem 25, extending upwardly 70 therefrom through the chamber 15, stuffing box 17 and gland 18, in which it is guided, and provided at its upper end with a knob or handle 26, which may be adjustably threaded thereon, as shown in Fig. 1, and secured in adjusted position by a lock nut 27. The lower end 29 of the stem 27 is reduced and threaded in the plunger 22, and passing through the valve disk 23, clamps it tightly in place in the recess in 85 the plunger in which it is fitted. The plunger is secured in place on the reduced threaded end 29 of the stem by a lock nut 30.

A restricted by-pass is provided to permit the liquid soap to flow from one side 90 of the plunger 22 to the other side thereof. This by-pass may be provided by a loose fit of the plunger 22 in the chamber 2, or as shown, by forming one or more openings through the plunger, such as notches 32 in 95 its periphery.

The plunger is thrust upward and the valve disk 23 is held normally against its seat 16 to close the opening from the chamber 2 into the chamber 15, by a spring 34 100 interposed between the plunger and the cover plate 11.

In the operation of the device the liquid soap with which the receptacle is supplied, flows by gravity through the nipple 7 and 105 passage 3, past the check valve 10, into, and fills the chamber 2, the exit from said chamber being closed by the valve disk 23. The pressure on opposite sides of the ball valve 10 is then equal, so that the valve is permit- 110

ted to drop by its own weight to the bottom of chamber 9 and rest upon seat 12.

Downward movement of plunger 22 causes displacement of a certain amount of the liquid soap trapped in chamber 2 below the plunger, this amount being forced through by-passes 32 to that portion of the chamber above the plunger. There is a difference between the capacity of chamber 2 above plunger 22 and the amount of soap displaced from the chamber below the plunger, this capacity being the lesser of the two because of the displacement of stem 25. An amount of liquid soap equal to this difference is accordingly expelled through spout 20. The soap filling the passage in the spout 20, is held in suspension and prevented from dripping therefrom by siphonic action, the chamber 15 forming the longer leg of a siphon, the shorter leg of which is formed by the downwardly curved outer end of the spout.

The upward or return movement of stem 25, under the action of spring 34, might or might not cause a certain amount of liquid soap to be expelled through spout 20, depending upon the combined areas of by-passes 32. If this area is comparatively small, there will be a difference between the amount of liquid soap displaced from that portion of chamber 2 above the plunger and the amount permitted to return through the by-passes to that portion of the chamber below the plunger, the latter amount being the lesser of the two. It is this difference that is expelled through spout 20 upon the upward or return movement of stem 25. In this case plunger 22 is double-acting. Upward movement of plunger 22 also decreases the pressure on the upper side of valve 10 so that the same is lifted from its seat and liquid soap permitted to flow past the valve and fill chamber 2. If, however, the combined areas of by-passes 32 is comparatively large, there will not be sufficient resistance to the passage of the soap through the by-passes to prevent the flow therethrough, to that portion of chamber 2 below plunger 22, of an amount at least equal to the amount displaced by the plunger from that portion of the chamber above the plunger. No soap will therefore be forced through spout 20 during the upward movement of the stem. At this time, however, the difference in displacement of plunger 22 and stem 25 will cause a decrease in pressure on the upper side of valve 10, so that the same is lifted from its seat. Soap from receptacle 5 will then flow past the valve until chamber 2 is filled, at which time the pressure on opposite sides of the valve will be the same, permitting the valve to drop by its own weight and rest upon seat 12, as explained above.

65 After the chamber 2 has been once filled,

the chamber 15 will be filled, and will remain filled with soap after each operation of the plunger 22, so that a predetermined quantity of soap will be delivered from the spout 20 with each complete reciprocation 70 of the plunger, until the receptacle 5 is emptied.

The quantity of soap discharged from the spout 20 by the movement of the plunger 22 may be varied by the adjustment of the lock 75 nut 27 and knob 26 on the stem 25, the nut 27 by engagement with the gland 18, acting as a stop to limit the downward movement of the plunger and thus determine the extent of its upward movement by the spring 80 34, and the quantity of soap forced thereby through the chamber 15 and spout 20.

The ball valve 10 is made of such size and weight that it will not be opened by the weight of the column of soap in the receptacle 5 and its connections with the dispenser when the plunger 22 is held in a depressed position. Continuous discharge of soap through spout 20 by holding stem 25 in its depressed position is thereby prevented. 85 Although the weight of ball valve 10 is such that it will normally remain on its seat 12 and prevent flow of the liquid soap from receptacle 12 into chamber 2, the weight of the valve is such that when plunger 22 is raised under the action of spring 34, the suction in chamber 2 will be sufficient to unbalance valve 10 so that the latter is lifted from its seat by the pressure of the liquid soap which then fills chamber 2, at which time the pressure on opposite sides of the valve will be equal to permit the latter to drop by its own weight upon seat 12.

Various modifications in the minor details of construction and arrangement of parts of the device may be made without departure from the principle and scope of the invention as defined in the following claims.

I claim:

1. In a liquid soap dispenser the combination of a case having a receiving chamber and an inlet passage opening into said chamber, a cap removably attached to the case and having a discharge chamber opening into the receiving chamber, a delivery spout connected with the discharge chamber, a plunger fitted in the receiving chamber and provided with a valve for closing the opening between said chambers, and operating stem attached to the plunger and extending through the discharge chamber, said plunger being provided with a passage connecting the parts of the receiving chamber on opposite sides of the plunger, a spring holding the valve normally against its seat, and an inwardly opening check valve in the inlet passage.

2. In a liquid soap dispenser the combination of a case formed with a receiving chamber and an inlet passage opening into it, a cap removably attached to the case and

having at its outer end a stuffing box and at its inner end a discharge chamber opening into the receiving chamber, a plunger fitted in the receiving chamber and provided with a by-pass opening into said chamber on opposite sides of the plunger and with a valve for closing the opening from the receiving chamber into the discharge chamber, an operating stem attached to the plunger and passing through the discharge chamber and stuffing box, a delivery spout attached to the cap in communication with the discharge chamber, a spring tending to shift the plunger towards the discharge chamber and to hold said valve closed, and an inwardly opening check valve in the inlet passage.

3. In a liquid soap dispenser the combination of a case formed with a receiving chamber and an inlet passage opening into the lower part of said chamber and enlarged adjacent thereto into a valve chamber, a ball check valve loosely fitted in said valve chamber and normally closing the inlet passage, a perforated cover plate seated in the receiving chamber over the valve chamber and confining the ball valve therein, a cap removably attached to the case and formed with a discharge chamber opening into the end of the receiving chamber opposite the valve chamber and provided with a delivery spout, a plunger fitted in the receiving chamber and provided with a by-pass and with a valve for closing the opening from the receiving chamber into the discharge chamber, an operating stem passing through the cap and attached to the plunger, and a spring tending to shift the plunger towards the discharge chamber and normally holding the plunger valve closed.

4. In a liquid soap dispenser the combination of a case formed with a receiving chamber and an inlet passage opening into one end of said chamber and provided with an inwardly opening check valve, a cap attached to said case and formed with a discharge chamber opening at one end into the other end of the receiving chamber and provided at the opposite end with a delivery spout, a plunger fitted to work in the receiving chamber and provided with a valve adapted to close the opening from the receiving chamber into the discharge chamber and with an operating stem passing through the discharge chamber, a restricted by-pass connecting the parts of the receiving chamber on opposite sides of the plunger, and a spring tending to shift the plunger towards the discharge chamber and to hold the plunger valve closed.

5. In a liquid soap dispenser the combination with a case formed with a receiving chamber and an inlet passage opening into

said chamber and provided with an inwardly opening check valve, a cap removably attached to the case and formed with a discharge chamber opening at one end into and of smaller diameter than the receiving chamber and with a valve seat around the opening into the discharge chamber, a plunger fitted in the receiving chamber, a valve disk mounted on the side of the plunger towards the discharge chamber, a restricted by-pass between the parts of the receiving chamber on opposite sides of the plunger, an operating stem passing through the discharge chamber in the cap and having a reduced end threaded in the plunger and clamping the valve disk thereto, and a spring interposed between the plunger and the opposite end of the receiving chamber and normally holding the valve disk against said seat.

6. In a device of the character described, the combination with a casing having a chamber and inlet and outlet passages therefor, and a check valve arranged at said inlet passage, of a plunger slidably fitted in said chamber and adapted to close said outlet passage and to provide a passage between opposite sides of said plunger when the latter is in position to close said outlet passage.

7. In a liquid soap dispenser the combination of a case formed with a receiving chamber and an inlet passage opening into one end of said chamber, a cap attached to the case and formed with a discharge chamber opening at one end into the other end of the receiving chamber and provided at the opposite end with a delivery opening, a plunger fitted to work in the receiving chamber and provided with a valve for closing the opening from the receiving chamber into the discharge chamber, an operating stem extending from the plunger through the discharge chamber, a restricted by-pass connecting the parts of the receiving chamber on opposite sides of the plunger, and a ball check valve seated by gravity in the inlet chamber and of such size and weight as not to be opened by the pressure of the liquid soap against it when the plunger valve is held open.

8. In a device of the character described, the combination with a casing having a chamber and inlet and outlet passages therefor, and a check valve arranged at said inlet passage, of a plunger slidably fitted in said chamber and adapted to close said outlet passage, said plunger being provided with a by-pass at the periphery thereof whereby the portions of said chamber on opposite sides of said plunger are connected when the latter is in position to close said outlet passage.

In witness whereof I hereto affix my signature.

HERMAN E. HEINE.
